UNITED STATES PATENT OFFICE

114,900

DESIGN FOR A CULINARY MOLD

Angelo Napolillo, Chicago, Ill.

Application October 13, 1938, Serial No. 80,431

Term of patent 14 years

To all whom it may concern:

Be it known that I, Angelo Napolillo, a citizen of the United States and a resident of Chicago, in the county of Cook and State of Illinois, have invented a new, original, and ornamental Design for a Culinary Mold, of which the following is a specification, reference being had to the accompanying drawing, forming a part thereof, and in which:

Fig. 1 is a top plan view of a culinary mold showing my new design;

Fig. 2 is a side elevational view of the same; and

Fig. 3 is a bottom plan view of the same as seen from line 3—3 in Fig. 2.

I claim:

The ornamental design for a culinary mold, as shown.

ANGELO NAPOLILLO.
